FOUNTAIN BRUSH

Ernest H. Bucknell and Irving A. Ward, both % Modern
Faucet Mfg. Co., 1700 E. 58th St., Los Angeles, Calif.

Filed June 20, 1962, Ser. No. 70,618

Term of patent 14 years

(Cl. D9—2)

FIGURE 1 is a side elevational view of a fountain brush showing our new designs;

FIGURE 2 is a top plan view;

FIGURE 3 is a bottom plan view;

FIGURE 4 is a front elevation;

FIGURE 5 is a rear elevation;

FIGURE 6 is a fragmentary perspective view thereof taken from left end of FIG. 1.

We claim:

The ornamental design for a fountain brush, substantially as shown.
